Primary Examiner — Jae Liang*Assistant Examiner* — Tia Ruth-Renee Polidori(74) *Attorney, Agent, or Firm* — Rumit Ranjit Kanakia**CLAIM**

The ornamental design for a folding water bottle, as shown and described.

DESCRIPTION

FIG. 1 is front elevational view thereof of a folding water bottle showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top perspective view thereof.

The portions of the folding water bottle shown in broken lines form no part of the claimed design.

1 Claim, 7 Drawing Sheets(56)
